ARTIFICIAL LEG

Noel F. Harrington, North Hollywood, Calif.

Application May 5, 1945, Serial No. 592,117

1 Claim. (Cl. 3—2)

1

My invention relates to artificial legs and has particular reference to an artificial leg which may be employed with either above the knee amputations or below the knee amputations.

Artificial legs which include a knee joint have been formed with the knee joint constructed as either a single bolt extending transversely through the knee joint about which the knee joint is to pivot or the knee joint has been formed of a pair of laterally spaced pivots, one on each side of the artificial leg to provide a pivotal action as near as possible to the center of pivotal action of the original human leg. All of these previous constructions have had the disadvantage that the knee joint pivot mechanism required a considerable mass of metal and metal and wood, adding excess weight to the knee joint which produced an inertia at the joint, preventing a natural freedom of action of the artificial leg.

Another disadvantage of such knee joints has been that the axis of the pivotal movement was disposed so near to the front of the leg as to render the leg unstable, particularly when the user was required to make a relatively high step.

It is therefore an object of my invention to provide an artificial leg structure in which the knee joint is disposed at the rear of the artificial leg to increase the stability of the leg.

Another object of my invention is to provide an artificial leg of the character described wherein the knee joint comprises a single light-weight hinge member disposed at the rear of the leg, the hinge pivoting about an axis disposed at the point of bending between the rear portion of the upper leg and the rear portion of the lower leg, the axis extending transversely of the leg to provide lateral stability.

Another object of my invention is to provide a structure of the character described particularly adapted for below knee amputations, in which the pivot between the upper leg portion and the lower leg portion of the artificial leg is employed for lateral stability while the motion between the upper and lower leg members is provided by the natural knee joint.

Other objects and advantages of my invention will be apparent from a study of the following specifications, read in connection with the accompanying drawing, wherein

Fig. 1 is an elevational view of my artificial leg applied to a below the knee amputation with the leg in the standing position;

Fig. 2 is a view similar to Fig. 1 but illustrating the position of the artificial leg parts when

2

the leg is in a bent position as when the wearer is sitting down;

Fig. 3 is a vertical sectional view of the artificial leg shown in Figs. 1 and 2;

Fig. 4 is a perspective view of a hinge employed between the upper and lower leg portions of the artificial leg shown in Figs. 1, 2 and 3; and

Fig. 5 is a longitudinal sectional view of the hinge joint illustrating a stop employed for limiting the hinge movement in one direction, taken along line V—V of Fig. 4.

Referring to the drawing, I have illustrated in Fig. 1 my artificial leg as comprising a lower leg member 1 and an upper leg member 2 interconnected by a single flat hinge member 3 to provide a hinging motion between the upper and lower leg members at the knee joint.

The particular form of artificial leg shown in Figs. 1, 2 and 3 is illustrated as being applied to a below the knee amputation wherein the lower leg portion 1 is provided with a suitable internal socket 4 into which the stump 5 of the natural leg may be inserted while the upper leg portion may be formed as a harness adapted to be wound about the upper portion of the natural leg and adjusted thereto as by means of lacings 6.

With my artificial leg applied to this type of amputation, it will be apparent that the frictional engagement of the lower portion of the natural leg within the socket 4 will provide a sufficient engagement therebetween to support the weight of the lower leg portion 1 so that the natural knee may be used to provide the knee joint action between the upper and lower artificial leg members. However, as will be understood, the artificial lower leg is subjected to rotary twists as well as to lateral bending moments as the wearer walks upon the artificial leg and it is necessary to provide a stability between the upper and lower leg members to resist such twisting or lateral bending motion. This may be readily accomplished by means of the hinge member 3 which comprises in effect a strap hinge, the lower element 1 of which may comprise a plate adapted to be secured to the lower leg member 1 as by means of screws 8. The upper end of the lower hinge element 1 is preferably rolled upon itself, as indicated at 9, to form a laterally extending cylindrical bearing which permits the pivotal attachment of an upper hinge element 10 thereto.

The central portion of the bearing of the lower hinge element is preferably cut away so as to receive a similarly rolled end 11 of the upper hinge element 10 whereby a pair of short pivot pins 12 and 13 may be threaded through the

hinge members 9 of the lower hinge element 7 and into conical sockets 14 formed in the bearing 11 of the upper hinge element 10.

Where the artificial leg is to be used with the below the knee amputation, the upper hinge element 10 is preferably formed as an elongated strap of metal adapted to slide longitudinally of a box-like structure 15 secured as by means of rivets or other suitable securing mechanism to the rear of the upper leg member or harness 2, the upper hinge element 10 being adapted to freely slide up and down within the box-like securing structure 15 limited only to motion between an extreme upper and an extreme lower position as by means of a pin 16 secured to the hinge element 10 and projecting through a vertically disposed slot 17 formed in the rear wall of the box structure 15.

It will be noted that the single hinge 3 is secured at the rear of the upper and lower leg members 1 and 2 and may be constructed of extremely light material, providing substantially little mass concentrated at the knee joint while the engagement of the hinge with the upper and lower leg members provides ample bracing to resist either a twisting motion between the upper and lower leg members or lateral bending thrusts which would be imposed upon the natural knee joint. By permitting relative motion between the box structure 15 and the hinge strap 10, the natural leg of the user is permitted to pivot around the natural knee joint without any interference with the hinge employed on the artificial leg, any bending of the upper and lower leg members resulting in the retraction of the strap 10 into the box-like structure 15 as illustrated particularly in Fig. 2.

Thus for below the knee amputations the artificial leg provides all of the support which is required with a minimum of artificial weight added to the natural leg and natural knee joint.

The essentials of this structure are equally adapted to above the knee amputations merely by omitting the slot 17 and securing the strap 10 either directly to the upper leg harness 2 or by omitting the slot 17 and securing the strap 10 within the box-like structure by the use of the pin 16 extending through a circular opening formed in the wall of the box structure 15 having a diameter equal to the diameter of the pin. With such structure the artificial leg, which includes both the upper leg portion and the lower leg portion hinged together by the hinge 3, provides all of the stability against twisting as well as lateral bending and at the same time provides a flexible hinge between these members, permitting the support of weight through the hinge.

When the device is adapted to either type of amputation, it is desirable to provide a stop, limiting the forward movement of the lower leg portion 1 in its hinging movement which may be readily provided by striking out a portion of the metal of the hinge element 10, as indicated at 18, and forming upon the lower hinge element 7 a hook-like projection 19, the end of which projects over the end 20 of the mid portion of the upper hinge element 10, as indicated in Figs. 4 and 5 so that as the lower leg is swung forwardly to a position of alignment with the upper

leg portion the hook 19 will engage the hinge element 10 and prevent further forward movement of the lower leg portion. If desired, a block 21 of fiber, rubber or other cushioning material may be secured on the end of the hook member 19 to act as a shock absorber, preventing unpleasant shocks to the wearer when the lower leg portion is brought to a stop.

In assembling the lower leg member 1 and the upper leg harness 2, I prefer to mount the harness upon the upper portion of the natural leg and then to dispose the lower leg member 1 in correct aligned position with the upper leg prior to the attachment of the hinge 3 to the lower leg member so that upon securing the hinge to the lower leg member the harness and leg member 1 will be in natural alignment with each other.

By employing pointed pivot pins 12 and 13 to engage the conical sockets 14, it will be apparent that any amount of pivotal adjustment of the hinge members may be readily accomplished to insure against undue friction or undue lost motion between the upper and lower leg members.

It will be understood from the foregoing description and the drawing that any suitable ankle structure may be employed but for the purpose of the foregoing description it is not deemed necessary to illustrate or describe such structure in any detail.

It will be apparent from the foregoing that an artificial leg constructed in accordance with my invention provides a sufficient support against twisting and lateral movements between the upper and lower leg elements with a minimum of weight required in the knee joint. In addition, it will be noted that the disposition of the hinge at the rear of the leg places the hinge action at a point at which the leg naturally tends to straighten out to align the upper and lower leg members while at the same time such disposition of the hinge leaves the knee free for bending movements without irritating constrictions such as accompany knee joints having pivotal hinges disposed at the sides of the knee.

While I have shown and described the preferred embodiment of my invention, I do not desire to be limited to any of the details of construction shown or described herein, except as defined in the appended claim:

I claim:

In an artificial leg, a lower leg member defining an artificial lower leg, ankle and foot to be disposed below the position of a natural knee of the wearer, an upper leg harness adapted to surround a portion of the upper natural leg, a single strap hinge disposed at the rear of said harness and said leg member, the pivot of the hinge being disposed in alignment with the natural knee joint and extending transversely of the lower leg joint, said strap hinge comprising a lower hinge element adapted to be secured to the lower leg member, an upper hinge element, a box-like structure secured to the upper leg harness for slidably receiving said upper hinge element, and means for limiting the amount of sliding movement permitted between said upper hinge element and said box-like structure.
